UNITED STATES PATENT OFFICE.

CHARLES E. PATTERSON, OF JACKSONVILLE, ILLINOIS.

INVALID BED.

Application filed April 21, 1926. Serial No. 103,542.

This invention relates to an invalid bed, one of the objects being to provide a structure of this character utilizing a supplemental or hammock frame having belts extending thereacross one or more of which can be removed at will or adjusted so as to add to the comfort of the patient or to facilitate handling the occupant of the bed.

A further object is to provide a supplemental structure of this type which, under normal conditions, is positioned with the belts resting upon a mattress of the usual type mounted on the bed, simple and efficient means being employed whereby the supplemental frame or hammock can be raised or lowered readily relative to the mattress.

A still further object is to combine with the supplemental frame a back lift which is yieldingly supported and by the use of which the patient can be supported comfortably in a sitting or reclining posture.

Another object is to provide an invalid bed which, when not in use can be folded or collapsed so as to occupy the minimum space, the construction of the bed being such that any of the working parts thereof can be easily operated by a person of average strength, the different adjustments being effected quickly and the entire structure being sufficiently durable to withstand any of the strains to which the device might be subjected under the severest tests while in use.

Another object is to provide means whereby the various necessary appurtenances may be properly combined with and adjusted relative to the bed.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

50 In said drawings,

Figure 1 is a side elevation of the bed, the supplemental frame or hammock structure being shown elevated and the back rest in position for use.

55 Figure 2 is a plan view.

Figure 3 is an elevation of one end of the bed.

Figure 4 is a transverse section on line 4-4, Figure 2.

Figure 5 is an enlarged side elevation of 60 a portion of one of the side members of the supplemental frame.

Figure 6 is a transverse section through the two side members of the supplemental frame, a belt being shown in engagement 65 therewith, a portion of the belt being broken away.

Figure 7 is a section on line 7-7, Figure 5.

Figure 8 is a side elevation of a portion 70 of the back rest and showing the yielding means employed for controlling the downward movement of the back rest.

Figure 9 is an enlarged transverse section through the tray used in connection with the bed, the supporting standard being 75 shown in elevation with portions broken away and the side rail of the bed being shown in section.

Referring to the figures by characters of reference 1 designates the corner post of the 80 bed pivotally connected as at 2, to the side rails 3 which are preferably T-shaped in cross section with the intermediate webs 3' extending inwardly as shown particularly 85 in Figures 4 and 9.

End frame members 4 connect the corner posts or legs and are likewise T-shaped in cross section. These end legs are connected by crossed braces 5 secured to the legs and serving to hold the legs at each end against 90 movement relative to each other. Additional braces 6 connect the corner posts or legs 1 to the side rails 3. These braces are detachably connected either to the legs or to the side rails and, when unfastened, will 95 allow the frames formed by the legs and braces 5 to fold relative to the side rails 3. Any desired means can be utilized for detachably securing these braces 6 at one or both ends.

100 Forked brackets 7 are mounted on the upper ends of the corner posts or legs 1 and the brackets on the posts or legs at the foot of the bed are provided with pulleys 8 while similar pulleys 9 are mounted in the brackets 7 at the upper ends of the other posts or legs 1. Pulleys 10 are journaled in the legs 1 below pulleys 8 and side rails 3 and additional pulleys 11 are journaled in the remaining posts 1 below the pulleys 9 and 110

the side rails 3. Brackets 12 are connected to the end frame members 4 at the centers thereof and journaled in these brackets is a longitudinal shaft 13 to one end portion of which is secured a ratchet wheel 14 adapted to be engaged by a pawl 15 whereby rotation of the shaft 13 in one direction can be prevented. Shaft 13 may be provided with a forked end 16 in which a crank arm 17 is pivotally mounted. By means of this crank arm the shaft 13 can be rotated in one direction.

Any suitable arrangement of slats S can be provided in the bed frame, these slats being supported preferably by the flanges 3' as shown in Figure 4. These slats are designed to support a mattress M of the usual or any preferred construction. A supplemental or hammock frame 18 is designed to rest upon the mattress M and is preferably formed of a metal tube or pipe bent to form the sides 19 and 20 of the supplemental frame and one end 21. The other end of the frame is formed of a separate length of pipe indicated at 22 coupled to the side 19 by an elbow 23 and to the side 20 by a coupling or union 24. Claim 18 is preferably longer than the frame of the bed so that the end portions thereof will project between the corner posts or legs 1 as shown particularly in Figures 1 and 2. Mounted on the side 19 of the supplemental frame 18 are sleeves 25 each of which is provided, at one end, with a toothed collar or ratchet 26 integral therewith. The sleeves 25 are held spaced apart by collars 27 mounted on the side 19 of the frame 18 and fastened in position by set screws 28 or any other suitable means. The collar 27 at one end of each sleeve 25 has an ear 29 extending radially therefrom in which is pivotally mounted a pawl 30. This pawl is so shaped as to engage the adjacent toothed collar or ratchet 26 so as to hold the sleeve against rotation in one direction as long as the pawl is in active position. Extended longitudinally of each of the sleeves 25 is a gripping strip 31 having slots 32 in the end portions thereof for the reception of retaining screws 33 or the like engaging the sleeves. The sleeves 25 can be of any length desired and any desired number of the sleeves can be used.

Secured to the side 20 of the supplemental frame are gripping strips 34 similar to and mounted in the same manner as the strips 31, these strips 31 and 34 being directly opposite each other, each strip 31 being of the same length as the corresponding strip 34 on the opposite side of the supplemental frame. Belts 35 are designed to be used in connection with the strips 31 and 34. One end of each belt 35 is inserted between one strip 34 and the side 20 and is then lapped about said side 20 so as to clamp upon that end portion of the belt in engagement with strips 34. Said belt is then carried over the opposed

sleeve 25 and is then inserted between said sleeve and the strip 31. By means of a spanner wrench or other suitable tool sleeve 25 is rotated so that the teeth of ratchet 26 will slip past the pawl 30. In this way the belt will be wrapped about sleeve 25 and the said belt can be made taut. Obviously any weight applied to that portion of the belt stretched across the frame will tend to bind the ends of the belt with increasing pressure against the side 20 or the sleeve 25 so that the belt will not become detached. However by loosening the belt so that there is no pressure upon it the ends can be withdrawn readily from positions back of the strips 31 and said belts can therefore be readily removed and other belts substituted therefor. Thus the belts can be easily cleaned by completely detaching them from the supplemental frame, it being possible to substitute clean belts for them. In using a spanner wrench for the purpose of rotating each sleeve 25, the same is preferably placed in engagement with the ratchet teeth 26.

Extending from the sides of the supplemental frame between two of the belts are upstanding brackets 36 to which are pivotally connected heads 37 each of which has an arcuate flange 38 along the bottom thereof. An arcuate series of apertures 39 is provided in each head and any one of these apertures is adapted to receive a pin 40 extending inwardly from the bracket 36, thus to hold the head against rotation about its pivot 41. A steel cable 42 is secured at one end to the forward portion of each of the arcuate flanges 38 and is attached at its other end to a spring 43. This spring is adjustably connected by a turnbuckle 44 or the like to the end portion 21 of the supplemental frame. This spring 43 obviously exerts a continuous pull through the steel cable 42 upon the arcuate portion 38 of the head 37. Consequently when a pin 40 is removed from each head 37, the said disks or heads 37 will be rotated by the springs. These disks or heads 37 are provided with sockets 45 in which are seated the lower ends of the sides of a frame 46 forming a part of a back rest. The sides of this frame are connected by an endless belt 47 which fits transversely around the frame. This belt can be easily slipped on or off of the frame as will be apparent by referring to Figure 2. Obviously when the pins 40 are removed the frame will swing upwardly under the action of the springs 43 so as to afford a comfortable back rest which will adjust itself automatically to the patient. After the back rest has been brought to a desired position the pins 40 can be inserted so as to prevent further movement. When not in use the back rest can be swung downwardly between the sides of the supplemental frame and there held by inserting the pins 40 in the proper

apertures 39. By means of turnbuckles 44 the tension of the springs can be regulated.

Secured to the sides of the supplemental frame 18 adjacent the ends thereof are ropes 48 arranged in pairs. These ropes are extended upwardly from the frame over the pulleys 8 and 9 and thence downwardly under the pulleys 10 and 11 respectively and inwardly to the shafts 13, the said ropes being securely attached to this shaft. Thus when the shaft 13 is rotated in one direction all of the ropes will be wound thereon and they will pull upwardly on frame 21 so as to elevate it relative to the mattress M. The supplemental frame can be held at any desired elevation by means of the pawl 15 in engagement with the ratchet 14.

Under normal conditions the supplemental frame is in its lowermost position with the belts 35 resting on the mattress. If the back rest is not to be used it can be removed bodily by disconnecting the heads or disks 37 from the brackets 36. When it is desired to raise the patient from the mattress the belts 35 are drawn taut and the supplemental frame 18 is elevated as heretofore explained. Any one of the belts can be adjusted while the patient is thus supported so as to provide the greatest comfort.

The patient while thus supported can be bathed readily and can be given any necessary attention. By loosening one belt at a time the same can be removed and another substituted therefor.

The particular construction of the bed lends itself readily to the attachment of various parts required in caring for patients. For example a sleeve 49 can be mounted to embrace and slide upon one of the side rails 3, this sleeve being provided with a bore extending therethrough from top to bottom as at 50 for the reception of a standard 51. This standard may be provided at its upper end with a laterally extending arm 52. Ears 53 engage this arm and extend downwardly from a tray 54. A collar 55 on the arm constitutes an abutment for one of the ears. A threaded stem 56 engages and extends from the free end of the arm 52 and has a spring 57 thereon confined between one of the ears 53 and a head 58 on the stem. Thus the spring serves to thrust one ear 53 tightly against the collar 55 so as to hold the tray at a desired angle. By sliding the tray against the ac-

tion of the spring 57, however, the same can be adjusted angularly so as to be supported in any desired position over the bed. By means of a set screw 59 the standard 51 can be secured firmly within the bore 50.

One or more sleeves 60 can be mounted to slide and rotate on the section 22 of the supplemental frame. Each of these sleeves can be held against movement by a set screw 61 and is formed with an extension 62 through which a bore is extended. This bore can receive a shank 63 extending from a foot rest 64 or it can receive a shank 65 of an extensor pulley 66. By providing two of these sleeves 60 both foot rest and the extensor pulley can be connected to the bed at the same time. Set screws 67 can of course be used wherever it is desired to hold any of the parts against movement relative to the sleeves 60. Obviously any other desired attachment can be used in lieu of or in addition to those already described.

What is claimed is:

The combination with a tubular frame, of a plurality of alining sleeves mounted for rotation on one side of the frame, collars mounted on said side of the frame between the ends of the sleeves, means for fastening the collars to said side of the frame to hold them against rotation and to hold the sleeves against longitudinal movement, a pawl pivotally mounted on each collar, a ratchet collar rotatable with each sleeve and normally engaged by the adjacent pawl, thereby to hold the sleeve against rotation in one direction, a retaining strip extending longitudinally of each sleeve, a belt having one end portion insertible between one of the sleeves and the retaining strip thereon, means for tightening said strip upon the inserted end of the belt, said end of the belt being foldable back over the retaining strip thereby to be compressed between the wraps of the belt when wound on the sleeve, and means for attaching each belt to the opposite side of the frame, each of the sleeves being rotatable independently of the other sleeve, thereby to effect independent adjustment of the belts by winding and unwinding them from the respective sleeves.

In testimony that I claim the foregoing as my own, I have hereto affixed my signature.

CHARLES E. PATTERSON.
